UNITED STATES PATENT OFFICE

2,372,673

FABRIC

Ezekiel J. Jacob, New York, N. Y., assignor to
Benjamin Liebowitz, New York, N. Y.

Application December 22, 1941, Serial No. 424,016

12 Claims. (Cl. 66—202)

The present application is a continuation in part of my prior United States patent application Serial No. 394,895, filed May 23, 1941, Pat. No. 2,313,344. This latter application is a continuation in part of my United States patent application Serial No. 330,504, filed April 19, 1940.

My present invention relates to new knitted fabrics.

It is an object of this invention to provide in a heat-resistant knitted fabric means adapted to diffuse the heat to which it is exposed throughout the entire fabric thereby diminishing the likelihood of the fabric being destroyed, e. g., by fusing of the glass or similar fibres of which the fabric is made.

A further object of my invention consists in incorporating in a heat-resistant knitted fabric means adapted to convey heat from one part of this fabric to another.

Still a further object of my invention consists in providing a heat-protecting non-combustible knitted fabric which is also adapted to be used for heating purposes.

Another object of my invention consists of a new non-combustible heat-resistant knitted fabric in which heating elements are incorporated in such a manner that any danger of burning by touching of the heated fabric is avoided.

Still another object of my invention consists of a new electrically-heated knitted fabric adapted to be used for various purposes, as for instance, for electrical hot pads, heated garments, aviator costumes, heated blankets, heated rugs and other heating means for rooms.

With the above objects in view, my present invention mainly consists of a knitted fabric made from non-combustible fibres i. e. filaments of ductile metals and of non-combustible electrically insulating fibres i. e. filaments of glass or similar substances. Naturally it is possible to combine with the non-combustible ductile metal and glass filaments also other non-combustible electrically insulating filaments. Thus for instance, my new knitted fabric may also be made from fibres i. e. filaments of ductile metals as nickel or nichrome, of glass, and of asbestos in combination.

In accordance with a preferred embodiment of my invention the new fabric is knitted of filaments of ductile metals and glass. The filaments of ductile metals, i. e., fine metallic electrically conductive wires are preferably inter-knitted with the heat-resistant electrically insulating glass filaments and form part of the knitted fabric itself.

I have found that by incorporating fine metallic wires into a knitted fabric made of fine-heat-resistant electrically insulating glass filaments which simultaneously are also of relatively low heat conductivity, I am able to reduce the tendency of these glass filaments of relatively low heat conductivity to burn out when locally exposed to a temperature appreciably above that which the fabric can otherwise withstand. The reason therefore is that the fine metallic wires incorporated in the heat-resistant glass fabric are of relatively high heat conductivity and distribute the heat over a greater surface, thereby reducing the temperature at the over-exposed region. Thus the heat-resistant electrically insulating glass or similar filaments are protected from being melted or otherwise damaged.

Glass filaments are especially well-adapted for the purpose of this invention: glass is heat-resistant and electrically insulating and can readily be drawn into extremely fine filaments. It is of particular advantage that yarns made of such filaments can be knitted into fabrics. As an example of a specific embodiment, yarns which are very satisfactory for the present purposes may be made by twisting together approximately one hundred glass filaments, each of which has a diameter of the order of magnitude of a few ten-thousandths of an inch; a number, e. g., six of the resulting yarns may be plied or twisted together to form the final yarn of which the desired fabric may be made.

These glass filaments, or the yarns made thereof, form the main part of the new fabric. Incorporated therein are the heat-resistant filaments of relatively high electric conductivity.

I propose to use non-combustible fibres of ductile metals as, for instance, fine metallic wires as such filaments. Suitable metals for these wires are, e. g., nickel, nichrome, chromium-nickel alloys, iron-nickel alloys and other metals having suitable electrical and thermal conductivity and preferably high resistance to oxidation at elevated temperature.

I have found that for certain purposes these metallic wires should preferably have a diameter of about .002 to .005 inch and be properly distributed throughout the heat-resistant electrically insulating filaments for the purpose in view.

The incorporated wires are also of importance as they mechanically strengthen the structure of the new fabric. By increasing the mechanical strength of the fabric, it retains its shape more easily; furthermore the wires when incorporated in an appropriate manner in a knitted

fabric, for instance a knitted tubing, hinder the fabric from unravelling. This function of the wire is also useful in the course of production of the fabric.

In the accompanying diagrammatic drawing I show preferred embodiments of my invention from which the same will be more clearly understood.

In this drawing:

Figs. 1 and 2 are enlarged fragmentary views of two modifications of fabrics knitted in accordance with the present invention; and

Figure 3 is a view of a new heating device incorporating a fabric of the type shown in one of the Figs. 1 and 2.

The new knitted purl fabrics shown in Figures 1 and 2 consist of yarns 12 of heat-resistant fine glass filaments inter-woven with thin metallic wires 14 having each a diameter of .002 to .005 inch. In experiments carried out by me, I have used nickel wire having a diameter of about .003 inch and having an electric resistance of about fifty-one ohms per foot; I also tried using nichrome wire having the same diameter and a resistance of about two hundred and thirty ohms per foot. I found that when I incorporated about twenty feet of such wire into a knitted fabric made of glass yarn and connected the ends of the wire with a source of electric current, these wires were heated to a sub-glow temperature adapted for heating purposes.

The purl fabric shown in Fig. 1 is knitted of yarns 12 of glass filaments and the metallic wires 14 lie between the courses 13 of this fabric and form small loops 15.

In the embodiment shown in Fig. 2 the knitting of the glass yarn is identical with the one shown in Fig. 1. The only difference is that the metallic wires lie not only between the courses 16 and 17 of the knitting, but the wire loops 18 form part of the courses 17.

As shown in Figs. 1 and 2 the metallic wires are substantially evenly distributed in the knitted fabric so that parallel wire portions are not in contact with each other, thereby avoiding the possibility of short circuits when the wire ends are connected to a source of electric current. Furthermore the distance and arrangement of the metallic wires is chosen in such a manner that they are spaced from one fabric surface, thereby avoiding the danger of electric shocks by touching this surface.

Fig. 3 shows a heating device making use of the knitted fabrics shown in one of the above-described figures.

In the embodiment shown in this figure several heating wires 28 are parallelly connected to the source of electric current 29 by means of the electric conductors 30 and 31. In this knitted fabric the conductors 30 and 31 are arranged in the longitudinal direction of the fabric along the edges thereof.

It is of importance that consecutive portions of the heating wire, for instance those wire portions which are parallel to each other, be insulated from each other in order to avoid short circuits; for this purpose the wires are interknitted with the glass, or other electrically insulating heat-resistant filaments in such a manner that some of these filaments are lying between consecutive wire loop portions, insulating them from each other.

Fabrics of the above-described type may be used for various heating purposes as for in-

stance, for electrical heating pads, heated garments such as aviators costumes, heated blankets, heating rugs and other heating means for rooms.

6 This fabric may also be used for heat insulating purposes as for instance, for fireplace screens and fireplace linings and the like.

It should, however, be stressed that it is also possible to use one and the same fabric for both purposes. Thus, for instance, it is possible to use a fireplace screen consisting of a fabric of the above-described type alternately as heat insulating means in usual manner, or as heating device; in the latter case it is only necessary to connect the ends of the wire or wires incorporated in the fabric of the screen with a source of electric current.

It should be stressed that I have found glass yarn especially adapted for the purposes of the present invention.

The specific embodiments shown and described above are merely illustrative.

What I claim as my invention and desire to secure by Letters Patent of the United States is:

- 10 1. A knitted fabric of glass filament yarn comprising wire incorporated in spaced courses.
- 15 2. A knitted fabric comprising glass filament yarn knitted in consecutive courses and wire incorporated in spaced courses.
- 20 3. A knitted fabric comprising glass filament yarn in consecutive courses and uninsulated thin metallic wires incorporated in said fabric spaced from each other and spaced from at least one surface of said fabric.
- 25 35 4. A knitted purl fabric comprising glass filament yarn knitted in consecutive courses and wire incorporated in spaced courses.
- 40 5. A knitted purl fabric of glass filament yarn comprising conductive thin metallic wire incorporated in spaced courses.
- 45 6. Knitted fabric comprising glass filament yarn knitted in consecutive courses and uninsulated thin metallic wires incorporated spaced from each other in at least a part of said courses.
- 50 7. A knitted fabric comprising heat resistant non-combustible, electrically insulating and non-conductive fine filaments yarn knitted in consecutive courses and uninsulated thin metallic wires incorporated spaced from each other in at least a part of said courses.
- 55 8. A knitted fabric of heat resistant non-combustible, electrically insulating and non-conductive fine filaments and wire incorporated in spaced courses.
- 60 9. A knitted fabric comprising heat resistant non-combustible electrically insulating and non-conductive fine filaments knitted in consecutive courses and wire incorporated in spaced courses.
- 65 10. A knitted fabric comprising heat resistant non-combustible electrically insulating and non-conductive fine filaments in consecutive courses and uninsulated thin metallic wires incorporated in said fabric spaced from each other and spaced from at least one surface of said fabric.
- 70 11. A knitted purl fabric comprising heat resistant non-combustible electrically insulating and non-conductive fine filaments knitted in consecutive courses and wire incorporated in spaced courses.
12. A knitted purl fabric of heat resistant non-combustible electrically insulating and non-conductive fine filaments and conductive thin metallic wire incorporated in spaced courses.

EZEKIEL J. JACOB.
